UNITED STATES PATENT OFFICE

168,505

BABY TEETHER

Robert M. Hayes, Weston, Mass.

Application April 18, 1952, Serial No. 19,386

Term of patent 14 years

(Cl. D83—1)

To all whom it may concern:

Be it known that I, Robert M. Hayes, a citizen of the United States, residing at Weston, in the county of Middlesex and State of Massachusetts, have invented a new, original, and ornamental Design for a Baby Teether, of which the following is a specification, reference being had to the accompanying drawing, forming a part hereof wherein

Fig. 1 is an elevational view of a baby teether, showing my new design; and

Fig. 2 is a side elevational view thereof.

I claim:

The ornamental design for a baby teether, as shown.

ROBERT M. HAYES.
